INVENTOR

James D. Hornbeck & Co.

UNITED STATES PATENT OFFICE.

JAMES D. HORNBUCKLE, SR., OF SAN JOSE, CALIFORNIA.

PROPELLER.

Application filed December 3, 1923. Serial No. 678,315.

To all whom it may concern:

Be it known that I, JAMES D. HORNBUCKLE, Sr., a citizen of the United States, and a resident of San Jose, in the county 5 of Santa Clara and State of California, have invented certain new and useful Improvements in Propellers, of which the following is a specification.

It is the object of my invention to provide an aeroplane that will occupy but small 10 space; that will permit of movement along a vertical axis; that cannot fall into a tail or nose spin; and that provides a covered compartment for the operator.

15 In the drawing:

Figure 1 is a side elevation of the device. Figure 2 is a plan view of the same.

Referring more particularly to the drawing, 1 indicates a rectangular framework 20 of light material covered with a light fabric 2 and having its upward forward portion sloping as at 3.

Securely mounted upon each side of frame 1 and extending a distance above its upper 25 edge, are bars 4 connected by a rotatable shaft 5 and forming a rigid support for said shaft midway the length of frame 1.

Mounted on shaft 5 to rock therewith is a plane 6 having side pieces 7 mounted 30 thereon, the plane 6 being somewhat longer and wider than frame 1. To each corner of plane 6 is attached a cable as indicated at 8—8 and 8^a—8^a, these cables passing over their respective pulleys 9—9 and 9^a—9^a to 35 a control lever 10 pivotally mounted at 11 on frame 1. It is obvious that a forward movement of lever 10 will tilt the forward end of the plane 6 upwardly, and a backward movement of the same will reverse 40 the position of the plane 6 to any desired angle.

At 12 is indicated a rudder pivotally mounted at 13 on frame 1 and controlled by means of cables 14—14^a attached thereto 45 and passing over their respective pulleys 15—15^a to control lever 10. A lateral movement of lever 10 will swing the rudder 12 to the right or left as desired.

At 16 are twin propellers mounted on 50 shafts 17 in bearings 18 arranged at the bottom of sloping portion 3 and designed to pass the air over frame 1—2 and under plane 6. These propellers are driven by means of gear and shaft connections 19 to engine 20, clutches 21—22 being inserted

between each propeller and the engine drive. By means of this construction either propeller may be operated at will, either independently of or in conjunction with the other. 60

The propellers are formed with curved blades 23 and a flange 24 located on the inner edge of the blade so that air caught by the blade will be caught also by the flange and thrown rearwardly of said propeller. 65

A pair of similar propellers 25—25 and 25^a—25^a are arranged upon vertical shafts 26—26 and 26^a—26^a upon opposite sides of frame 1—2 and above the plane thereof as shown. These propellers are similar in construction to propellers 16 and are operated in any suitable manner as by gear and shaft connections 27—27^a to engine 20, a clutch being inserted in said connections as at 28. 70

It may be readily seen from the foregoing description that the propellers 16 may be operated together or independently by operating clutches 21—22, and the side propellers may be thrown into or out of action by clutch 28. 75

It might be readily seen from the foregoing description that the construction of the plane 6 is such that while it may be tilted as desired the side pieces 7 prevent the air from being carried off sideways and confine it to the under side of the plane during its passage thereover. The inside flanges on the propeller blades in a similar manner confine the direction of flow of the air in such a manner as to secure the greatest 80 power therefrom. 85

Upon plane 6 is arranged a gas bag 29 which when filled with a suitable gas lighter than air substantially offsets the weight of the framework 1—2 and consequently assists in effecting a vertical movement in ascending or descending, besides stabilizing the whole structure. 90

It is to be understood, of course, that while I have herein shown and described one specific embodiment of my invention, changes in form, construction, proportions, and method of operation may be made within the scope of the appended claims. 100

I claim:

1. In an aeroplane a propeller comprising a plurality of rectangular blades arranged at substantially right angles to its axis of rotation, each blade being curved to bite into the air and having a flange formed on 110

one edge only and extending at right angles to its operative surface and on the inner edge thereof and extending from the center to the outer edge of the propeller.

2. In an aeroplane a propeller comprising a plurality of blades arranged at substantially right angles to its axis of rotation,

each blade being curved to bite into the air and having a flange formed on one edge only and extending at right angles to its operative surface and on the inner edge thereof and extending from the center to the outer edge of the propeller.

J. D. HORNBUCKLE, SR.
